UNITED STATES PATENT OFFICE.

FRANK W. SNEDDEN, OF WILKINSBURG, PENNSYLVANIA.

DESIGN FOR AN AUTOMOBILE SIGNAL-LIGHTS CASING.

Application filed June 27, 1927. Serial No. 22,582. Term of patent 3½ years.

To all whom it may concern:

Be it known that I, FRANK W. SNEDDEN, a citizen of the United States of America, residing at Wilkinsburg, in the county of Allegheny and State of Pennsylvania, have invented a new, original, and ornamental Design for an Automobile Signal-Lights Casing, of which the following is a specification.

Referring to the accompanying drawing forming a portion of this specification—

Figures 1 and 2 are, respectively, front and side elevational views of an automobile signal lights casing, showing my new design.

What I claim is:

The ornamental design for an automobile signal lights casing, substantially as shown.

In testimony whereof I affix my signature.

FRANK W. SNEDDEN.
